COCKTAIL BAR

John W. Constable and Thomas D. Bibby, Clear
Lake Highlands, Calif.

Application October 28, 1941, Serial No. 416,898

2 Claims. (Cl. 62—89)

This invention relates to a cocktail bar, the general object of the invention being to provide a compactly arranged device containing refrigerating means for forming ice cubes, cooling bottles containing liquid and having a chilled water supply system associated therewith, with compartments for containing various objects for facilitating mixing cocktails and other drinks and for keeping articles of various kinds in a chilled state.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a rear view of the device.

Figure 2 is a top plan view thereof.

Figure 3 is a section on the line 3—3 of Figure 1.

Figure 4 is a section on the line 4—4 of Figure 2.

In these views the letter A indicates a cabinet, the walls of which are provided with suitable insulating means *a* and said cabinet has a high front wall with a bar forming top part 1 extending rearwardly at right angles from the front wall with the side walls extending up to the part 1 and from the rear portion of this part 1 the sides slope downwardly and rearwardly as shown at 2. A refrigerating chamber 3 is formed in the upper portion of the front of the cabinet, the rear wall 4 of which has openings therein for the passage of the ice trays and these openings are closed by the doors 5, the hinges of which are shown at 6. The bottom of the chamber is shown at 7 and slopes downwardly and forwardly and terminates short of the front wall of the cabinet so as to form a drip or drain board. The trays are shown at 9 and the refrigerating coil is shown at 10.

A work board or shelf 11 extends horizontally across the rear portion of the cabinet below the sloping upper edges of the side walls and a downwardly and forwardly sloping chamber forming member 12 has its open top located between the lower edge of the partition wall 4 and the front edge of the shelf 11, this member 12 forming a bottle receiving well.

A horizontal partition 13 is spaced below the shelf 11 and extends from the member 12 to the

5 rear wall of the cabinet and these parts 11 and 12 form a space for receiving the drawers 14. Vertical and horizontal partitions 15 and 16 are located in the cabinet below the parts 13 and 12 and form a plurality of compartments for receiving various kinds of articles and access to these compartments is provided by means of the doors 17 in the rear wall of the cabinet.

Refrigerating coils 18 are located in the cabinet 10 in suitable positions for chilling materials or liquids placed in the various parts thereof and, of course, these coils 18 and the coil 10 are connected to suitable refrigerating means. A cold water coil 20 is located in the cabinet and is 15 suitably connected to a source of supply and a pipe 21 leads from the upper end of the coil to a spigot 22 carried by the wall 4. An ice receiving tray 23 depends from the central portion of the shelf 11 and is located under the spigot and 20 suitable drain pipes 24 lead from the various parts of the apparatus which lead draining to a drain outlet in the bottom of the cabinet.

If desired doors can be provided for closing the rear portion of the top of the cabinet by 25 engaging the sloping walls 2 and drawers can be placed in all or some of the partitions formed by the partitions 15 and 16.

Thus it will be seen that I have provided a compact arrangement of parts, the top of the 30 cabinet forming a bar on which drinks and the like can be placed so that they can be reached by customers or persons standing in front of the device with means in the upper portion of the cabinet for forming ice cubes, other means 35 in which bottles can be placed to cool liquid therein, these bottles being accessible by the bartender by reaching over the shelf 11 to reach the bottles in the casing 12 and the bottles can be placed on the shelf 11 while mixing drinks. 40 The drawers 14 can be used for receiving various articles such as lemons, limes, oranges and the like while the tray 23 will receive a surplus supply of ice. Also chilled water can be secured by turning on the spigot 22 and other articles to 45 be chilled can be placed in the compartments formed by partitions 15 and 16 and these compartments can be made to form drawer receiving spaces instead of being closed by the doors 17.

It is thought from the foregoing description 50 that the advantages and novel features of the invention will be readily apparent.

It is to be understood that changes may be made in the construction and in the combination and arrangement of the several parts pro-

vided that such changes fall within the scope of the appended claims.

Having described the invention, what is claimed as new is:

1. In a cocktail cabinet, a cabinet having a high front portion the top of which forms a bar including a rear wall, means in the high portion for forming ice cubes, a rear shelf forming member located below the plane of the ice forming means, and a forwardly and downwardly inclined bottle well located between the rear edge of the shelf forming member and the rear wall of the bar, and drawers located under the shelf forming portion.

2. In a cocktail cabinet, a cabinet having a high front portion the top of which forms a bar including a rear wall, means in the high portion for forming ice cubes, a rear shelf forming member located below the plane of the ice forming means, a forwardly and downwardly inclined bottle well located between the rear edge of the shelf forming member and the front wall of the bar, drawers located under the shelf forming portion, and refrigerating coils in the cabinet, some of which act to keep the contents of the bottles in the well chilled.

JOHN W. CONSTABLE.
THOMAS D. BIBBY.
